UNITED STATES PATENT OFFICE

VASCOE C. BAIRD, OF OWENSBORO, KENTUCKY

STOVEPIPE-CLEANING DEVICE

Application filed February 20, 1928. Serial No. 255,806.

This invention relates to contrivances or devices for the purpose of removing soot from within stove-pipes; and a mechanism of an extremely simple character is permanently disposed within the said pipe with a small crank exposed and accessible, and whereby by rotating same a few revolutions the device will be actuated in such a manner as to revolve a spirally disposed wire which is arranged closely to the inner wall of the vertical and horizontal pipes, and thereby effectively and positively loosen and remove all of the soot and the like that has accumulated therein, and causing the settlement in the vertical pipe to fall within the stove, while that in the horizontal pipe will be carried into the flue of the chimney.

As the invention after once installed, will remain permanently in the original position, the necessity of handling the pipe at any time is entirely eliminated; which is indeed a decided advantage and the need of which has been long felt by those whom are almost daily in contact with stoves and similar fire-burning devices.

While I have herein disclosed one precise embodiment of my invention, it is therefore subject to certain minor changes in the details of construction, in the event that the same would become necessary in the practical development of the device for the market. However, in such an event the general principle as hereinafter described and later claimed, will not of course become thereby affected.

The accompanying drawings form an important part of this illustration; and the numerals therein correspond to similar ones in the following detailed description: and, Figure 1 is a reduced view of the complete device as it is applied to the vertical and horizontal stove-pipes; and said pipes and a partial view of the flue being in section; also a portion of the connecting stove in plain view.

Figure 2 is a transverse section on line 1—1 of Figure 3; but in an upright position.

Figure 3 is a view taken upon the line 2—2 of Figure 1.

Figure 4 is a sectional view upon the line 3—3 of Figure 5.

Figure 5 is an elevation taken at the line 4—4 of Figure 1.

The invention comprises properly a framework having a strip of metal indicated by the numeral 1, and which has ends 2 formed as shown and connected to the stove-pipe by rivets 3 which pass through holes in the said ends for same. A bevel-gear 4 is secured to horizontal shaft 5 by pin 6, and one end of said shaft is supported by strip of metal 7 which is soldered to the portion 1 of the framework and carries bushing 8 for said end and cotter pin 9 as indicated. The opposite end of shaft 5 rotates within bushing 10, which is pressed into an opening for same in the said stove-pipe, and which is clearly indicated in Figure 2. It is also noted that the end 11 of shaft 5 is formed into a crank 12 which receives a handle portion 13.

Internally threaded sleeve or coupling 14 is provided, and is adapted to receive the externally threaded end of the shaft 5, and a similarly threaded end of portion 11; and the object of said coupling being that the unit now being described may be placed into the stove-pipe as a whole, and the portion 11 of said shaft drawn up into same from the outside thereof, in the installation of the device 80 for permanent use.

Small bevel-gear 14 is provided and is secured to vertical shaft 15 by pin 16. With reference to Figure 2 it will be seen that a strip of metal 17 is formed as shown and soldered to the part 1 of the framework, and which has an opening in the top portion thereof to receive bushing 18, and there is also a similar bushing 19 in portion 1, both of which bushings are for the shaft 15.

Sleeve 20 is securely pressed upon the upper end of shaft 15, and has a lateral opening therein to admit of the passage of one end of the spirally disposed wire 21 which wire is attached to said sleeve by bending sharply, as at 21A.

Still referring to Figure 2 it is clearly seen, that by rotating the shaft 5 by the handle 12, sleeve 20 upon the vertical shaft 15 will likewise rotate and simultaneously turn the end of 100

the wire 21, and as said wire extends through practically the entire length of the vertical stove-pipe, it is readily seen that the said pipe will be efficiently cleaned by this operation.

5 A particular advantage of the device is the fact that it provides a means by which the horizontal, as well as the vertical, section of the stove-pipe will also be cleaned in the single operation. To accomplish this a mechanical unit is disposed within the elbow of the stove-pipe, and is composed of a strip of metal 22 which has ends 23 with openings therein, and secured to the said elbow by rivets 24; also a strip of metal shown at 25 and soldered to strip 22 as indicated; and which make up the framework for this unit, and which is clearly seen in Figures 1 and 4.

Similar bevel-gears 26 and 27 are provided, and gear 26 is secured to the vertical shaft 28 by the pin 29, while the gear 27 is likewise secured to horizontal shaft 30 by pin 31, and bushings 32 are mounted in strip 22, and bushings 33 in strip 25 for the aforesaid respective shafts.

25 Spirally disposed wire 34 is employed to operate within the horizontal section of the stove-pipe, and one end thereof passes through an opening in sleeve 35, which is pressed upon shaft 30, and said wire sharply bent, as at 34A; while sleeve 36 is likewise connected to vertical shaft 28 and also has an opening therein to receive the end 21B of the wire 21, and sharply bent as thereby indicated.

35 From the foregoing description it is now understood that the upper and lower units are permanently connected, and that the operation of the said lower unit will simultaneously actuate the said upper unit, thereby effectively cleaning the vertical and horizontal sections of the stove-pipe, and which may be clearly interpreted by referring particularly to Figure 1.

A very important fact is that the entire mechanism of the device is of a very simple construction, and of the lowest valued materials consistent with the requirements, and in this connection all of the bevel-gears indicated may be of a similar material, as the duty 50 they are to perform does not of course necessitate a great amount of strength. The general framework of both units may be composed of a medium-light sheet metal, and likewise the shafts and other parts are of a 55 simple and low-valued material.

Having thus described my invention, what I claim as new is:

1. In a device of the character described, a lower mechanical unit disposed within a 60 stove-pipe, said unit comprising a framework of a metal strip, having the ends thereof formed at right angles thereto, and secured to the wall of the said pipe, a metal strip secured upon the top portion of the first- 65 named strip, a horizontal shaft with a large

bevel-gear secured thereto, a vertical shaft with a smaller bevel-gear secured to same, both of the aforesaid gears to properly mesh, means upon the first-named strip to support one end of the said horizontal shaft, and the last-named strip having means to support the said smaller gear and shaft for same; an internally threaded coupling disposed upon the said horizontal shaft for the purpose of admitting the said lower unit of the device into the stove-pipe as a whole, and a crank extending at its inner end into said stove-pipe and connected to the threaded coupling.

2. In a device of the character described, a lower unit secured within a stove-pipe, including a horizontal and a vertical shaft, a large bevel-gear upon the horizontal shaft, and a smaller bevel-gear upon the vertical shaft, said gears to mesh, and the said shafts for same to rotate in bearings within the said framework; a sleeve disposed upon the upper end of the said vertical shaft, a spirally disposed wire within the said stove-pipe and means connecting the sleeve to the end of the said wire so that same will rotate when the said mechanism is actuated.

3. In a device of the character described, a lower mechanical unit disposed within a vertical stove-pipe, actuated by an externally arranged crank, a spirally disposed wire within the said stove-pipe, one end of which is connected to the said unit; an upper mechanical unit disposed within the elbow of the stove-pipe, said unit comprising a metal strip with the ends thereof formed so as to conform to the said elbow, and secured thereto, an additional metal strip completing the framework of the said upper unit, a vertical shaft and a horizontal shaft mounted on said strips, a bevel-gear secured to each of the said shafts, and said gears to properly mesh; a sleeve disposed upon the outer end of each of the said shafts, a spirally disposed wire to operate within the horizontal section of the said stove-pipe, and one end thereof connected to the said sleeve of the aforesaid horizontal shaft, and one end of the said spiral wire within the vertical section of the said stove-pipe connected to the sleeve of the said vertical shaft, so that when the aforesaid lower unit is actuated by the said external crank therefor, the said spirally disposed wire within the vertical and horizontal sections of the stove-pipe will simultaneously rotate within the said pipes, specifically for the purpose disclosed.

In testimony whereof I hereunto affix my signature.

VASCOE C. BAIRD.
